UNITED STATES PATENT OFFICE.

EDWARD H. BASTABLE, OF SOUTH BRAINTREE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WORK-SUPPORT.

1,337,190.

Specification of Letters Patent. Patented Apr. 20, 1920.

Application filed July 20, 1916. Serial No. 110,309.

To all whom it may concern:

Be it known that I, EDWARD H. BASTABLE, a citizen of the United States, and resident of South Braintree, in the county 5 of Norfolk and State of Massachusetts, have invented certain Improvements in Work-Supports, of which the following description, in connection with the accompanying drawings, is a specification, like reference 10 characters on the drawings indicating like parts in the several figures.

The present invention relates to work supports and more particularly to devices for use in connection with such supports 15 to prevent injury to the upper and lining of a shoe.

During a number of the operations performed in manufacturing a shoe it is necessary to mount the shoe upon a work support 20 port or jack which ordinarily comprises a last pin or spindle adapted to enter the thimble hole or last pin socket in the heel end of the last. The length of the last pin is usually somewhat less than the depth 25 of the thimble hole and the last is supported by a last supporting shoulder at the base of the last pin which engages the cone of the last. The portion of the shoe upper extending beyond the cone of the 30 last, being without support, has a tendency to fall in over the cone of the last and, unless considerable care is exercised when the shoe is jacked, the upper and lining are caught between the cone of the last and the 35 last supporting shoulder and damaged when pressure is applied to the last.

It is an object of the present invention to provide a simple and efficient device for shielding the last supporting surface of a 40 work support which will engage and spread the shoe upper away from the last supporting surface and the sides of the last during the mounting of the shoe upon the work support.

To this end one feature of the present invention consists in the provision of a shoe upper spreading device normally disposed longitudinally of the last and arranged for movement into upper spreading position 50 transversely of the last as the shoe is placed upon the work support.

Other objects and features of the present invention will be apparent from the

following description when considered in connection with the accompanying drawings and the novel features will be set forth 55 in the appended claims.

In the drawings,—

Figure 1 is a view in side elevation of a well known type of shoe jack embodying 60 the preferred form of the present invention;

Fig. 2 is an enlarged end elevation with the shoe and last in cross section illustrating the upper spreading member in normally inoperative position; and

Fig. 3 is a view similar to Fig. 2 illustrating the position of the upper spreading member after the shoe has been placed upon the last pin.

The invention is herein shown by way of illustration as embodied in a shoe jack of the type known as the "Crispin" jack but it is to be understood that the invention may also be used to advantage in any type 75 of work support in which the last is mounted upon a last supporting seat which engages the cone of the last.

The illustrated work support to which the improved upper and lining protector device of the present invention is applied comprises an adjustable bracket 2 having a forwardly projecting arm 4 upon which an adjustable toe post 6 is mounted. Pivotally secured on the bracket for movement 80 toward the toe post 6 is a heel block 8 provided with an upright last pin or spindle 10 adapted to be received in a thimble hole or last pin socket 12 in the heel end of the last 14.

To prevent the upper and lining from being caught between the cone of the last and the heel block 8 when the last is mounted upon the shoe support the last pin 10 is provided with an upper and lining protector device which is adapted to spread the upper away from the sides of the heel end of the last and the supporting block before the cone of the last engages its supporting surface. In the illustrated preferred embodiment of the invention the upper spreading member comprises a collar 16 which is slidably and rotatably mounted on the last pin 10. This collar is provided with two oppositely and laterally extending upper 100 engaging wings or arms 18 which when dis-

posed transversely of the last project a distance beyond the sides of the heel end of a last.

The last pin 10 is provided with a cam slot 20 extending substantially parallel to the axis of the last pin for a greater part of the length of the last pin and near the top of the last pin extending spirally of the last pin, preferably a distance approximately one quarter of the circumference of the pin. This cam slot receives a stud 22 projecting from the collar 16 of the upper spreading member. The upper spreading member is normally and yieldingly sustained at the upper end of the cam slot 20 or at the top of the last pin by a spring 24 surrounding the last pin and interposed between the collar 16 and the bottom of a socket provided in the last supporting block 8 at the base of the last pin. The cam slot 20 is so formed on the last pin 10 that in the normally inoperative position of the upper spreading member at the top of the last pin the arms 18 are disposed substantially longitudinally of a supported shoe or in the direction of the length of the last as illustrated in Fig. 2 and in the operative upper spreading position of the upper spreading member, as illustrated in Fig. 3, the arms 18 are disposed substantially transversely of the last. The top of the wings 18 are formed so as to provide a substantially flat supporting surface for the cone of the last and preferably, in the inoperative position of the upper spreading member, they extend somewhat above the end of the last pin to engage the cone of the last before the last pin enters the last pin socket. The downward movement of the upper spreading member 16 is limited by engagement with the heel block 8 upon which it seats itself to support the shoe. When the last is forced downwardly upon the last pin the cone of the last engages the wings 18 of the upper spreading member whereupon the upper spreading member is immediately rotated from its normal inoperative position with the arms 18 disposed substantially longitudinally of the last into a position in which the wings are disposed substantially transversely of the last during which rotative movement the wings act to thrust the shoe upper and lining outwardly away from the sides of the last and the last supporting surfaces on the heel block and on the upper spreading member.

The transverse upper spreading position of the arms 18 relatively to the last is not thereafter changed during the further downward movement of the upper spreading member 16 into last supporting position upon the heel block 8. When the shoe is removed from the jack the spring 24 acts to return the upper spreading member into normal inoperative position at the top of

the last pin. This construction provides a simple and compact protector device which operates with a certainty to spread the shoe upper and lining away from the last and last pin when the shoe is mounted upon the support.

Although in the illustrated preferred embodiment of the invention the upper spreading device is given only a quarter of a rotation about the last pin, it is obvious that the upper spreading member may be given any desired amount of rotative movement without departing from the spirit of the invention.

Having described my invention, what I claim as new and desire to secure by Letters Patent of the United States is:—

1. A support for a last having, in combination, a last pin, upper spreading devices mounted on the last pin and normally disposed substantially longitudinally of the last, and means for moving the upper spreading devices into upper spreading position substantially transversely of the last as the last is being mounted upon the last pin.

2. A support for a last having, in combination, a last pin, upper spreading devices mounted on the last pin and normally disposed within the planes of the sides of the last, and means for rotating the upper spreading devices into position to project beyond the sides of the last to spread the upper outwardly as the last is being mounted upon the last pin.

3. A support for a last having, in combination, a last supporting seat, shoe upper spreading devices associated with said last supporting seat, and means for rotating the upper spreading devices about an axis substantially perpendicular to the last supporting seat into position to move the shoe upper away from the last supporting seat as the last is being mounted upon it.

4. A support for a last having, in combination, a last pin, an upper spreading member mounted upon the last pin and having laterally extending upper engaging arms normally disposed substantially longitudinally of the last, and means for moving the upper spreading member into position to dispose the upper engaging arms substantially transversely of the last to spread the upper outwardly as the last is placed upon the last pin.

5. A support for a last having, in combination, a last pin, an upper spreading member mounted upon the last pin and having laterally extending upper engaging arms normally disposed within the sides of a last, and connections between the last pin and the upper spreading member constructed and arranged to rotate the upper spreading member into position for the upper engaging arms to project beyond the sides of the last pin.

last to spread the upper outwardly as the last is being mounted upon the last pin.

6. A support for a last having, in combination, a last pin, an upper spreading member mounted upon the last pin having laterally extending upper engaging arms normally disposed substantially longitudinally of the last, means to sustain yieldingly the upper spreading member at the upper end 10 of the last pin, and connections between the upper spreading member and the last pin constructed and arranged to rotate the upper spreading member into position to dispose the upper engaging arms substantially 15 transversely of the last to spread the upper outwardly as the last is being mounted upon the last pin.

7. A support for a last having, in combination, a last pin, an upper spreading member mounted upon the last pin and having laterally extending upper engaging arms normally disposed substantially longitudinally of the last, a support for the upper spreading member, a spring to sustain the 20

upper spreading member at the upper end 25 of the last pin, and a pin and cam slot connection between the upper spreading member and the last pin constructed and arranged to effect a rotation of the upper spreading member into position to dispose 30 the upper engaging arms substantially transversely of the last during its downward movement upon the application of the last to the last pin.

8. A support for a last having, in combination, a last supporting seat, shoe upper spreading means associated with said last supporting seat, and means for moving the shoe upper spreading means in a plane substantially parallel to the last bottom as the 40 last is being mounted upon the last supporting seat from an inoperative position to a position to move the shoe upper away from the last supporting seat.

In testimony whereof I have signed my 45 name to this specification.

EDWARD H. BASTABLE.
